UNITED STATES PATENT OFFICE.

GEORGE E. SMITH, OF OIL CITY, LOUISIANA.

FOLDING COACH STEP.

Application filed August 27, 1923. Serial No. 659,583.

To all whom it may concern:

Be it known that I, GEORGE E. SMITH, a citizen of the United States, residing at Oil City, in the parish of Caddo and State of Louisiana, have invented a new and useful 5 Folding Coach Step, of which the following is a specification.

This invention aims to provide a novel means whereby the lower tread of a set of 10 steps on a passenger coach may be raised and lowered at the will of an operator, thereby rendering it unnecessary for a train attendant to carry a stool, as is now the custom, the stool being used to lessen the 15 space between the lowermost tread and the ground, novel means being supplied for operating the tread and for holding it in a lowered position.

It is within the province of the disclosure 20 to improve generally and to enhance the utility of devices of that type to which the invention appertains.

Within the scope of what is claimed, a 25 mechanic may make many changes in the particular form shown, without departing from the spirit of the invention, the drawings showing a preferred form, but not the only one in which the invention may be embodied.

30 In the drawings:

Figure 1 shows in plan, a device constructed in accordance with the invention;

Figure 2 is a side elevation wherein parts 35 appear in section; and Figure 3 is a section on the line 3—3 of Figure 2.

In carrying out the invention, there is provided brackets 1 adapted to be secured in any suitable way to the frame work of a 40 passenger coach or other vehicle. The brackets 1 carry a frame 2 supported in part by braces 3, secured at their upper ends, as at 42, to the frame 2, and attached at their lower ends to the frame by securing elements 30. The lower members of the frame 45 2 are designated by the numeral 4. The frame 2 carries the treads 5 and the risers 6 of a fixed stairway.

Depending rearwardly foldable hangers 8 are connected by securing elements 7 with 50 the lower members 4 of the frame 2, a rearwardly foldable riser 9 being carried by the hangers 8. The numeral 10 marks a foldable tread connected by pivot elements 11 with the lower ends of the hangers 8. 55 Through the outer edge of the foldable tread 10 extends a rod 12, whereon are pivoted

the lower ends of upwardly foldable knuckle joint braces 14, the upper ends of the braces 14 being carried by the securing elements 7. Upwardly foldable knuckle joint braces 15 60 are connected at their ends with the securing elements 30 and with the pivot elements 12, sleeves 40 being mounted on the rod 12, between the braces 14 and 15, as indicated in Figure 1. Levers 16 are fulcrumed intermediate their ends on the securing elements 7, links 17 being pivoted to the lower ends of the levers 16, the lower ends of the links 17 being carried on the pivot members 18 which connect the parts of the foldable 65 knuckle joint braces 15. The links 17 have flanges 19, which, coacting with the levers 16, hold the links and the levers in the position shown in Figure 2.

Longitudinal braces 20 are secured intermediate their ends to the frame 2 as shown at 21, the upper ends of the braces being secured at 22 to the brackets 1. The lower ends of the braces 20 are carried by the securing elements 17. The lower end of a 70 support 23 is mounted on the securing element 30, the support being attached at 24 intermediate its ends, to one of the braces 20. One end of a track 25, in the form of a rod is mounted on the upper end of the 75 support 23. The other end of the track or rod 25 is carried in any desired way. In order that the device may be attached in one piece to a car, the upper end of the track 25 is mounted in an arm 26 on the uppermost tread 5, although the upper end of the track 25 may be taken care of in any desired 80 way, so far as its mounting is concerned.

A guide 27 is secured at its upper end to the frame 2, and is connected to the support 23. In the guide 27, a slide 28 is mounted for reciprocation, the slide 28 carrying an upstanding frame 29 provided with a handle 31. The slide 28, the frame 29 and the handle 31 may be designated generally 90 as a carriage, mounted for reciprocation on the fixed stairway, whereof the treads 5 and the risers 6 constitute part. The handle 31 carries a spring actuated grip 32 of known form, mounted to reciprocate on the track 25, the grip including levers 33 adapted to be pinched together, to release the hold of the grip 32 on the track. A glance at Figure 1 of the drawings will show the general construction of the grip 32 and a descent 100 into details is not necessary, since the grip 110 is of common form, and in view of the fact

that various sorts of grips may be used without departing from the spirit of the invention.

Assuming that the parts are arranged as shown in Figure 2, the upper ends of the levers 16 are swung downwardly and forwardly, the links 17 causing the foldable braces 15 to knuckle upwardly. This sets the hangers 8 and the riser 9 free, so that these parts can be folded backwardly. The foldable joint braces 14 are knuckled upwardly thus setting the tread 10 free, so that the same can move upwardly and backwardly. The grip 32 is released from the track 25 and, through the instrumentality of the handle 31 the carriage 28—29—31 is moved rearwardly, the slide 28 moving rearwardly in the guide 27. Since the slide 28 is connected at its lower end to the rod 12 in the foldable tread 10, the tread 10 is carried upwardly and rearwardly and the hangers 8 and the riser 9 are carried upwardly and rearwardly beneath the lowermost one of the fixed treads 5 of the stairway. When the levers 33 are released, the grip 32 will engage the track 25 and hold the parts in the positions shown in dotted line in Figure 2.

What is claimed is:

1. In a device of the class described, a fixed stairway, a track on the stairway, a guide on the stairway, a carriage interen-

gaged slidably with the track and with the guide, means for holding the carriage in adjusted positions, a foldable riser pivoted to the stairway, and a foldable tread pivoted to the riser, the tread being connected to the carriage.

2. In a device of the class described, a fixed stairway, a track on the stairway, a guide on the stairway, a slide mounted for reciprocation on the guide, a frame carried by the slide, a handle on the frame and mounted for reciprocation on the track, means carried by the handle for gripping the track, a foldable step pivoted to the stairway, and means for connecting the step with the slide.

3. In a device of the class described, a fixed stairway, a foldable step pivoted to the stairway, a track carried by the stairway, a carriage mounted for reciprocation on the track, means for holding the carriage in adjusted positions on the track, and means for connecting the carriage to the step.

In testimony that I claim the foregoing as my own, I have hereto affixed my signature in the presence of two witnesses.

GEORGE E. SMITH.

Witnesses:

W. J. HOLZINGER,
F. C. O'LEARY.
